UNITED STATES PATENT OFFICE.

BENJAMIN ROSETSTEIN, OF NEW YORK, N. Y.

DESIGN FOR A DOLL.

41,730.

Specification for Design.

Patented Aug. 29, 1911.

Application filed May 1, 1911. Serial No. 624,453. Term of patent 3½ years.

To all whom it may concern:

Be it known that I, BENJAMIN ROSETSTEIN, a citizen of the United States, residing in the city of New York, in the county of Kings, State of New York, have invented a new, original, and ornamental Design for a Doll, of which the following is a specification, reference being had to the accompanying drawing, forming part thereof.

I claim—

The ornamental design for a doll as shown.
BENJAMIN ROSETSTEIN.
